UNITED STATES PATENT OFFICE

2,623,339

PACKAGE WRAPPING MECHANISM

Oscar Sandberg, Toledo, Ohio, assignor to Lynch Corporation, Anderson, Ind., a corporation of Indiana

Application August 20, 1947, Serial No. 769,613

3 Claims. (Cl. 53—135)

1

This invention relates to a package wrapping mechanism and particularly to means for holding a wrapper for articles in position while moving the articles, with the wrapper partially in place, into a folder head or the like. The invention constitutes a variation in the wrapper hold down mechanism shown in my copending application Serial No. 712,970, filed November 29, 1946, for Package Wrapping Mechanism.

It is an object of the invention to provide a package wrapping mechanism having a wrapper hold down feature which requires a minimum of parts and dispenses with complicated leverage systems, mechanical movements and timing devices.

It is another object of the invention to provide a wrapper hold down mechanism which effectively prevents slippage of the wrapper relative to the article to be wrapped during part of the wrapping operation and which does not crush or injure fragile articles, such as cookies, crackers or cracker sandwiches.

It is a further object of the invention to utilize an essential element of a folding head of a wrapping machine as the hold down mechanism and to thus dispense with unnecessary parts and mechanical means of operating and timing such parts.

It is still another object of the invention to dispense with the necessity for timing the wrapper hold down mechanism of a wrapping machine.

It is an additional object of the invention to provide a spring biased, pivoted plate on the folding head of a wrapping machine which serves the dual purpose of providing a portion of a receiving pocket for the partially wrapped articles and also operates as a hold down means for the wrapping material during its movement into said pocket.

With these and other objects in view, the invention consists in the construction, arrangement and combination of the various parts of my device whereby the objects contemplated are attained, as hereinafter more fully set forth, pointed out in the claims and illustrated in the accompanying drawings, wherein:

Figure 1 is a top plan view of a folding head constructed in accordance with this invention;

Figure 2 is a side elevational view of the folding head;

Figure 3 is an enlarged detail view of the mounting for the wrapper hold down mechanism;

Figure 4 is a sectional view of the folding head and a portion of the wrapping machine showing the position of the parts as a partially wrapped package is being ejected from the folding head; and

Figure 5 is a view similar to Figure 4 showing the article to be wrapped being raised into the

2

folding head together with the wrapping material.

Referring specifically to the drawings for a detailed description of the invention, numeral 11 designates generally the folding head, numeral 12 a table for wrapping material 10, numeral 13 a lifting ram, numeral 14 a forked ejecting member or push rod, and numeral 15 a movable bell crank lever for opening the pockets of the folding head. The folding head 11 is rotated clockwise one quarter of a turn at a time, the ram 13 is raised, the ejecting member 14 is reciprocated horizontally and the bell crank lever 15 is oscillated, all at timed intervals by suitable mechanism which is not shown because it is well understood in the art. An example of such mechanism is clearly shown and described in my aforesaid copending application Serial No. 712,970.

The folding head 11 comprises two stub shafts 16 and 17 on which a casting is mounted. The casting includes two end plates 18 and 19 with a square connecting post 21. At the center of the post 21, two cross passages 22 are provided at right angles to each other having four connecting portions 23.

Each end plate 18 and 19 has journaled there-in a rod 24. It will be noted that four of the rods 24 are provided and that the folder head 11 has four article receiving pockets, each formed by a flat plate 25 and arcuate plates 26 and 27. The flat plates 25 are secured to the post sections 23 so that they are fixed with respect to the rotary folder head 11. The arcuate plates 26 are secured to the rods 24. The arcuate plates 27 are secured to rods 28 which are journaled in two bearings 29 secured to the stationary flat plates 25.

The folded head includes compression plates 31 and 32, one for each of the four pockets of the head. Each plate 31 is carried by a rod 33 which is fixed with respect to the folder head by being carried in the end plate 18. Each plate 32 is carried by a rod 34 which is slidable in end plate 19 and is biased inwardly by a spring 35. The inward limit of movement is determined by a stop collar 36 on the outer end of rod 34 which strikes the end plate 19. The inner end of the spring 35 bears against a collar 37 on rod 34.

The stub shafts 16 and 17 are journaled in suitable bearings (not shown) and the entire head is periodically rotated one quarter of a revolution. Means is also provided to automatically open the lowermost pocket as the ram 13 rises. This means consists of a bell crank lever 38—39 pivoted at 41 and carrying a pin 42 at the lower end of arm 38. The pin 42 is adapted to engage a projecting pin 43 which extends at a right angle from the rod 24. The bell crank lever 38—39 is rocked to the position shown in Figure 5 to rotate the lowermost plate 26 to permit entry of an article into the pocket of the folder

head. After the article and its wrapper 10 have entered the pocket, the bell crank 38-39 is rocked counterclockwise and the ram 13 is lowered. The plate 26 is then rotated to the closed position by tension springs 44 connected to the extensions 45 on rod 24 and to the pins 46 in end plates 18 and 19.

The article also pushes the lowermost arcuate plate 27 upwardly from the position shown in Figure 5 to the position shown in Figure 4. The plates 27 are biased and tend to rotate because of coil springs 47 secured to one of the bearings 29 and to a collar 48 secured to shaft or rod 28, as best shown in Figure 3. A second collar 49 is secured to shaft 28 and is provided with a stop pin 51 which strikes the flat plate 25 and limits rotation of the arcuate plate 27. The plates 26 and 27 and the plates 31 and 32 cooperate to retain the partially wrapped package in the pocket. The spring pressed plate 27 also holds the wrapper 10 in position on the article as the article is being raised into a pocket by ram 13.

The wrapper 10 is preferably fed to the wrapping machine in roll form, which is cut into proper lengths, as shown for example in my Patent 2,833,096. The wrapper is fed on to the table 12 in flat form beneath a pair of wrapper control rods 52 and 53. One of the rods is capable of slight floating movement and the space between the rods is normally slightly less than the diameter of the article. The rods thereby effect a close wrapping of the wrapper 10 around the article.

The pusher rod 14 is forked, as shown at 15, so that it will straddle the arcuate plates 27 when ejecting a package, as shown best in Figure 4. The pusher rod 14 is operated by any suitable means in properly timed relation to the folding head and ram movement.

A lever arm 50, having a lug 50a thereon, is provided and the lug 50a is positioned to engage the pin 43 on rod 24 to dispose plate 26 in the open position when the article is ejected by pusher rod 14. The lever arm 50 is operated in proper timed relation to pusher rod 14 by any suitable linkage (not shown).

A folding plate 54, which is biased toward the folding head by a spring 55, is provided to wrap the wrapper 10 around the article and seal the same, as shown in Figure 5. Heating elements 56 are provided in plate 54 to effect sealing, the wrapper 10 usually being cellophane or similar material. As the article and the wrapper are ejected, the ends of the wrapper are folded down by suitable folding plates generally indicated at 51.

From the foregoing it will be apparent that I have provided an improved folding head for a wrapping machine which is less complicated than former heads and which insures that the wrapping material will not slip relative to the article during the wrapping process.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. Means for retaining a wrapper in position

relative to an article while they are elevated by a ram for entering a pocket of a folding head of a package wrapping machine comprising a spring biased plate pivoted to the folding head in a position to engage with and be moved by the article as it is elevated into position by the ram, and a second pivoted plate for retaining the article and wrapper in the pocket after the ram moves out of engagement with the article, said plates being curved, the first one to wipe the article and wrapper with a small portion of the plate and finally contact a substantial portion thereof and the second one to embrace the article and wrapper sufficiently to effect retention thereof in said pocket.

2. Means for retaining a wrapper in position relative to an article while they are elevated by a ram for entering a pocket of a folding head of a package wrapping machine comprising a pivoted and spring biased plate for each pocket, said spring biased plate being pivoted on and carried by the folding head in a position to engage with and be swung by the article as it is elevated into position by the ram, means associated with each pocket for retaining the article and wrapper therein when the ram disengages from the article and the head is rotated, said last means comprising a second pivoted and spring biased plate for each pocket swingable to a position for engaging and partially embracing the article and the wrapper in the pocket, and means for moving said second plate to an open position while the ram is elevating an article and wrapper into the pocket for that plate.

3. Means for retaining a wrapper in position relative to an article while they are elevated by a ram for entering a pocket of a folding head of a package wrapping machine comprising a spring biased plate pivoted to the folding head in a position to initially engage at its outer end with, and be moved by, the article as it is elevated into position by the ram, said plate first occupying a position within the pocket and finally a position adjacent the top and one side thereof, means for retaining the article and wrapper in the pocket after the ram moves out of engagement with the article, said last means comprising a second spring biased plate pivoted in a position at the opposite side of said pocket for engaging the article and the wrapper in the pocket, means for moving said second plate to an open position while the ram is elevating an article and wrapper into the pocket, and means for ejecting said article and wrapper from said pocket.

OSCAR SANDBERG.
